UNITED STATES PATENT OFFICE.

WINFIELD S. THORP, OF NEW YORK, N. Y.

GAME APPARATUS.

1,095,436.

Specification of Letters Patent.

Patented May 5, 1914.

Application filed April 5, 1913. Serial No. 759,210.

To all whom it may concern:

Be it known that I, WINFIELD S. THORP, a citizen of the United States, residing at New York, in the county of New York and State 5 of New York, have invented new and useful Improvements in Game Apparatus, of which the following is a specification.

This invention relates to a device which is especially adapted for exhibiting the plays 10 made on a ball field distant from the device.

The object of the invention being to show a baseball field visible from any part of a hall, theater or any desirable building or in the open, upon which is shown by means of 15 devices representing the players, and a device for playing the game, the movements of the ball and players on any part of a distant field.

The device is designed to illustrate the 20 movements of flies, grounders, fouls and thrown balls, to any part of the field, thus representing every play made during the progress of the game, from a description received from the grounds by telephone, telegraph or ticker.

The device consists of a support or board 25 representing a ball field on a reduced scale, movable members denoting players are arranged on the support, and a universally 30 movable sphere representing the base ball can be moved to any portion of the field.

The foregoing device is adapted for all games where a ball and performers are in motion.

35 The novel features of the invention are more fully described in the following specification and claims and illustrated in the accompanying drawing in which:

Figure 1 represents a front elevation of a 40 device embodying this invention. Fig. 2 is an end elevation of the same. Fig. 3 is a similar view on a larger scale. Fig. 4 is a plan view of a bracket. Fig. 5 is a detail section of one of the channel portions of the 45 support. Fig. 6 is a detail section showing a base runner disk. Fig. 7 is a detail section showing a player disk. Fig. 8 is a modification of a disk.

In these drawings the letter *a* designates 50 a support which is preferably made of wood but could be constructed of sheet iron, slate or other material. In practice this board is about 10 feet square, and it can be positioned upright or preferably placed at an angle as 55 indicated in Fig. 2. The face and rear of the board can be marked to show the line

of a field *b*, a diamond *c* and foul lines *d* extending from first and third base, to the end of the field. The spaces *e* on the face of the board around the field may be used to depict 60 seating stands. On each side of the seating stands as may be determined will be spaces *f* for the names of the competing teams indicating who is at the bat and their individual record. The innings can be tallied beneath at *g*, all to be operated by cards or lights. The diamond *c* is cut entirely free from the field allowing for a continuous slot *i* the function of which will be hereinafter 65 described. The diamond is fastened to the main support by means of braces *j* best seen in Fig. 6, secured to the rear of the support. The playing field can be covered with a green smooth surfaced material or preferably with a heavy napped fabric *h* as indicated in Fig. 6, with narrow slots cut to correspond and somewhat concealing the slots in the board. The field is also provided with slots *k* formed to any suitable angle for a 70 purpose hereinafter specified. The sides of the slots may also have light metal guides *m* to prevent wear on the material *h* and to furnish smooth runners. 75

A series of devices such as disks *n* are arranged on the support. These disks represent 80 the players or fielders and are preferably movable along the slots *k*; the fielders can thus make their individual and collective play. These disks may be stationary as shown in Fig. 8; in this construction the 85 slots are omitted and the disk is fastened to the face of the board. The batter *o* or player of the opposing team is moved along a slot forming a continuation of the slot *i*, from a small house or cover *p* to the home plate. 90 This member *o* consists of a flexible disk secured to a stem *q* and having a button *y* secured to its opposite end. This disk is adapted to be moved along the slot *i* in the diamond to make the circuit of the bases, but 95 when necessary or when the player is out, the disk can be pulled through the slot by an operator stationed at the back of the support, and the player will disappear. The field disks *n* may be made of rigid material and 100 painted a distinctive color to distinguish from the base runner disks *o*. These disks *n* are only movable along the slots *k* to make the necessary plays and cannot be pulled through the slots. 105

Mounted on the support *a* is a ball *r* of 110 rubber, cork, aluminum or other material.

This ball is secured to a rod *s* extending from the home plate through a slotted bracket *t* secured to the top of the support. The upper portion of the rod has a yoke *u* 5 preferably an integral portion of the rod with a downwardly extending rod *v* passing through the slotted bracket and having a connection *w* at its lower end. A pendulum rod *x* extends loosely through a slot in the bracket and is swingingly mounted at 15 to the said yoke. The said rod has attached to its lower end a sphere or ball 16 corresponding to the ball *r* on the front of the support. The said ball 16 has secured to it a rear- 10 wardly projecting arm 17 on which is slid- 15 ingly mounted the connecting member *w* of the downwardly extending rod mentioned above.

A guide 18 on the face of the support 20 keeps the ball *r* a certain distance from the board to clear the player disks.

A series of channels or grooves 19 are arranged on the back of the support. The channels extend radially from the diamond 25 or home plate to the outfield and serve to guide the ball 16 thereby keeping the playing ball in a straight line to the field.

The rods *s* and *v* can both oscillate on the slotted bracket, hence when the connection *w* 30 is slid along the arm 17 it will swing the ball *r* forwardly away from the support, and by pushing the connecting member upwardly the ball will move to any part of the diamond or field. The operating connec- 35 tions *w* can also swing to and fro to carry the ball laterally over any portion of the diamond or field. In this connection it should be noticed that the playing ball *r* by means of its operating devices is given uni- 40 versal movement in order to illustrate fly balls, grounders, fouls and any play accom- plished by the two opposing teams in a game 45 of baseball. In other words the playing ball *r* is controlled by the movement of the operating connection, while the ball 16 swinging on the pendulum rod indicates to the operator stationed at the back of the board the location of the playing ball.

It should be said that the rear of the sup- 50 port is laid off with a diamond, field and foul lines the same as the face of the support, so that the operator stationed at the rear of the support will be able to see by means of the pendulum ball 16 the exact location of 55 the playing ball relative to the face of the support. The pendulum ball 16 at all times moves in unity with the oscillating, and up and down motion of the playing ball; but at

the forward movement at right angles to the support or backward movement toward the 60 support of the playing ball, the pendulum ball remains in contact with the back of the support to guide its course.

I claim:

1. In a game apparatus the combination 65 with a support representing a ball field, means universally mounted on the support to represent the movements of a ball, a pen- dulum arranged at the back of the support for manually controlling the movement of 70 the universal means.

2. In a game apparatus the combination 75 with a support representing a ball field, means universally mounted on the support to represent the movement of a ball, a pen- dulum connected to the universal means, and devices carried by the pendulum and connected to the universal means for man- ually controlling said means.

3. In a game apparatus the combination 80 with a support representing a ball field, a bracket located at the upper portion of the support, a ball carrying rod and an oper- ating rod universally mounted on the bracket, a pendulum connected to the rods 85 to position the ball.

4. In a game apparatus the combination 90 with a support representing a ball field, a bracket located at the upper portion of the support, a ball carrying rod and an actuati- 95 ng rod universally mounted on the bracket, a pendulum swingingly suspended from the rod and connected to the lower portion of the actuating rod to position the ball.

5. In a game apparatus the combination 95 with a support representing a ball field, slots situated in the support, flexible headed disks representing players mounted in the slots, and devices swingingly mounted on the sup- port to position the ball.

6. In a game apparatus the combination 100 with a support representing a ball field, slots located in the support, flexible headed disks representing players mounted in the slots adapted for movement along the slots and 105 for withdrawal by an operator at the back of the support, and devices universally mounted on the support to position a ball.

In testimony whereof I have hereunto set my hand in the presence of two subscribing 110 witnesses.

WINFIELD S. THORP.
